CLAIM

The ornamental design for a protective case for wireless tracker, as shown and described.

DESCRIPTION

FIG. 1 is a perspective view of a protective case for wireless tracker showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the protective case for wireless tracker shown in a configuration of use where a wireless tracker is received in the protective case for wireless tracker; and,

FIG. 10 is another perspective view of the protective case for wireless tracker shown in the configuration of use where the wireless tracker is separated from the protective case for wireless tracker.

(Continued)

The broken lines in the drawings depict portions of the protective case for wireless tracker that form no part of the claimed design.
